UNITED STATES PATENT OFFICE.

ERNST O. HÖHN, OF CHARLOTTENBURG, GERMANY, ASSIGNOR TO GENERAL ELECTRIC COMPANY, A CORPORATION OF NEW YORK.

TURBINE.

1,118,419.

Specification of Letters Patent. Patented Nov. 24, 1914.

Application filed April 30, 1914. Serial No. 835,420.

To all whom it may concern:

Be it known that I, ERNST O. HÖHN, a citizen of the Swiss Republic, residing at Charlottenburg, Germany, have invented 5 certain new and useful Improvements in Turbines, of which the following is a specification.

The present invention relates to steam or gas turbines.

10 The object of the invention is to provide an improved system for operating and controlling the nozzle valves of turbines wherein the valves are under the control of a single regulator or pilot valve and are caused to successively open and close in accordance 15 with the demand.

For a consideration of what I believe to be novel and my invention, attention is directed to the accompanying description and 20 claims appended thereto.

The drawing is a more or less diagrammatic view with the parts shown in section of an arrangement embodying my invention.

25 Referring to the drawing, 2 represents diagrammatically a rotor as a bucket wheel mounted on shaft 3 and receiving motive fluid from the sets of nozzles or other fluid discharging devices 4, 5, 6, 7, and 8. The 30 first set of nozzles 4 are always in communication with the steam chest 9. The others are controlled by the valves 10, 11, 12, and 13, which are operated respectively by motors 14, 15, 16, and 17, each of which comprises a cylinder in which moves a piston connected to the corresponding valve stem.

35 18 is an ordinary form of regulator or pilot valve, the heads 19 of which normally cover the openings 20 and 21. Operating 40 fluid, such as steam, air, oil, or water, is admitted between the heads 19 by way of pipe 22, and is discharged through openings 23 and 24 and outlet 25. The size of the openings 23 and 24 may be regulated by the 45 needle valves 26.

27 is a pipe connecting the opening 21 to the space beneath the piston of motor 14.

28 and 29 are a series of pipes connecting the spaces below and above the pistons of 50 the respective motors in series. These connections are so spaced that when any valve is seated its piston covers the end of the pipe 28 leading from it to the next cylinder, while

55 when open the piston covers the inlet end of the pipe 29 leading from the preceding cyl-

inder. The space above the last piston is connected by pipe 30 to the opening 20 of the pilot valve. The pilot valve is controlled by the movable abutment 31, which is subjected on its upper side to the pressure of 60 the region surrounding the nozzle valves; i. e., the pressure in steam chest 9, by way of passage 32, and on its lower side to a constant pressure, as that of the motive fluid, by way of passage 33. A proper balance is 65 effected by means of the adjustable spring 34. The supply of motive fluid to the turbine is controlled by the throttle valve 35 operated by the speed governor 36 through 70 a suitable motor mechanism 37.

The operation is as follows: Assume that the turbine is operating and the valves 10, 11, 12, and 13 are all closed. If now an increase in load occurs, the governor will open the valve 35 to admit more steam. If this is 75 in excess of what can be handled by the nozzles 4, the pressure in steam chest 9 will build up, causing piston 31 to lower and heads 19 to uncover openings 20 and 21. The pilot valve will then permit motive fluid 80 to flow through pipe 27 to the space beneath the piston of motor 14, thereby causing the same to move and open valve 10. As soon as the valve opens steam will be admitted to nozzles 5. This will cause a lowering of 85 the pressure in the region surrounding the valves and the piston 31 will operate to cause the pilot valve heads 19 to again cover ports 20 and 21. The opening of the valve 10 causes the piston of motor 14 to uncover 90 the end of pipe 28 leading therefrom to the next motor 15. If, due to further load, more steam is admitted than can be taken care of by nozzles 4 and 5, the pressure will again 95 build up, and piston 31 will be operated to cause the pilot valve to admit motive fluid under the piston of motor 15 by way of pipe 27, cylinder of motor 14, and pipe 28. The piston of motor 15 will thus be operated to 100 open valve 11 and at the same time will uncover the end of pipe 28 leading to motor 16 and cover the end of pipe 29 leading from motor 14. This operation can be repeated 105 until all the valves are open. In case of a falling off of the load the reverse action takes place, as will be apparent, the valves 10 to 13 being closed in reverse order to their opening.

By means of the needle valves 26, the 110 openings 23 and 24 can be regulated to re-

strict the flow and build up a pressure on one side or the other of heads 19 so as to retard the restoration of the same by piston 31 until such time as the motors 14, 15, etc., 5 shall have had ample time to fully open or close their valves, as the case may be. For example, if, due to an increase in the pressure in steam chamber 9, piston 31 has lowered, the fluid forced out by way of pipe 30 10 and opening 20 will be retarded by the constricted opening 23, thereby building up a pressure above the upper head 19 tending to hold the piston 31 lowered, and retarding its return to normal position for a sufficient 15 time for the full opening of the nozzle valve.

In accordance with the provisions of the patent statutes, I have described the principle of operation of my invention, together with the apparatus which I now consider to 20 represent the best embodiment thereof; but I desire to have it understood that the apparatus shown is only illustrative, and that the invention can be carried out by other means.

What I claim as new and desire to secure by Letters Patent of the United States, 25 is:—

1. The combination in a turbine, of fluid discharging means, valves controlling the flow of fluid thereto, a piston for each valve, 30 a cylinder for each piston, a regulator for controlling the supply of actuating fluid to the cylinders, means connecting the regulator and cylinders so that said regulator may cause the piston to operate to successively open the valves and to close them in the reverse order, a movable abutment for controlling the regulator, said abutment being subjected to the pressure in the region of the controlling valves on one side and 35 to a substantially constant pressure on the other, a main valve mechanism controlling the admission of operating fluid to the discharging means, and a governor for the same.

2. The combination in a turbine, of fluid discharging means, valves controlling the flow of fluid thereto, a piston for each valve, 40 a cylinder for each piston, a regulator for controlling the supply of actuating fluid to the cylinders, two sets of pipes, one set connecting the spaces above and the other the spaces below the pistons in series, said pipes being so spaced that when any valve is closed its piston covers the end of the pipe leading from the space below to the piston 45 of the next succeeding cylinder, and when any valve is open its piston covers the end of the pipe leading to the space above the piston from the preceding cylinder, pipes connecting the first and last cylinders to the regulator so that the regulator may cause the pistons to operate to successively open the valves and to close them in the reverse order, a movable abutment for controlling the regulator, said abutment being 50 subjected to the pressure in the region of the controlling valves on one side and to a substantially constant pressure on the other, a main valve mechanism controlling the admission of operating fluid to the discharging means, and a governor for the same.

controlling valves on one side and to a substantially constant pressure on the other, a main valve mechanism controlling the admission of operating fluid to the discharging means, and a governor for the same.

3. The combination in a turbine, of fluid discharging means, valves controlling the flow of liquid thereto, a piston for each valve, a cylinder for each piston, a regulator for controlling the supply of actuating fluid to the cylinders, means 60 connecting the regulator and the cylinders so that said regulator may cause the pistons to operate to successively open the valves and close them in the reverse order, a movable abutment for controlling the regulator, 65 said abutment being subjected to the pressure in the region of the controlling valves on one side and to a substantially constant pressure on the other, means for restricting the outlet openings of said regulator so as 70 to retard the flow therefrom, a main valve mechanism controlling the admission of operating fluid to the discharging means, and a governor for the same.

4. The combination in a turbine, of fluid discharging means, valves controlling the flow of fluid thereto, a piston for each valve, a cylinder for each piston, a regulator for controlling the supply of actuating fluid to the cylinders, two sets of pipes, one set connecting the spaces above and the other the spaces below the pistons in series, said pipes being so spaced that when any valve is closed its piston covers the end of the pipe leading from the space below to the piston 90 of the next succeeding cylinder, and when any valve is open its piston covers the end of the pipe leading to the space above the piston from the preceding cylinder, pipes connecting the first and last cylinders to the regulator so that the regulator may cause the pistons to operate to successively open the valves and to close them in the reverse order, a movable abutment for controlling the regulator, said abutment being 95 subjected to the pressure in the region of the controlling valves on one side and to a substantially constant pressure on the other, a main valve mechanism controlling the admission of operating fluid to the discharging 100 means, and a governor for the same.

In witness whereof, I have hereunto set my hand this 4th day of April, 1914.

ERNST O. HÖHN.

Correction in Letters Patent No. 1,118,419.

It is hereby certified that in Letters Patent No. 1,118,419, granted November 24, 1914, upon the application of Ernst O. Höhn, of Charlottenburg, Germany, for an improvement in "Turbines," an error appears in the printed specification requiring correction as follows: Page 2, line 67, for the word "liquid" read *fluid*; and that the said Letters Patent should be read with this correction therein that the same may conform to the record of the case in the Patent Office.

Signed and sealed this 26th day of January, A. D., 1915.

[SEAL.]

R. F. WHITEHEAD,

Acting Commissioner of Patents.
